US00D589713S

(12) **United States Design Patent**
Lowsky

(10) **Patent No.:** **US D589,713 S**
(b4) **Date of Patent:** **** Apr. 7, 2009**

(54) **CHAIR**(76) Inventor: **Jamie Lowsky**, 7000 Island Blvd., Apt. 106, Aventura, FL (US) 33160(**) Term: **14 Years**(21) Appl. No.: **29/329,198**(22) Filed: **Dec. 10, 2008**(51) LOC (9) Cl. .... **06-01**(52) U.S. Cl. .... **D6/379; D6/370**(58) **Field of Classification Search** D6/334–336, D6/369, 370, 374, 375, 376, 379, 492, 500–502; 297/411.3, 411.44, 445.1, 446.1, 451.9, 452.63, 297/452.64

CLAIM

The ornamental design for a chair, as shown and described.

DESCRIPTION

FIG. 1 is a perspective view of my ornamental design;
FIG. 2 is a right elevation view of the ornamental design of FIG. 1;
FIG. 3 is a left elevation view of the ornamental design of FIG. 1;
FIG. 4 is a front elevation view of the ornamental design of FIG. 1;
FIG. 5 is a rear elevation view of the ornamental design of FIG. 1;
FIG. 6 is a top plan view of the ornamental design of FIG. 1;
FIG. 7 is a bottom plan view of the ornamental design of FIG. 1; and,
FIG. 8 is a perspective view of the ornamental design of FIG. 1 with broken lines showing cushions, which are shown for illustrative purposes only and form no part of the claimed design.
